UNITED STATES PATENT OFFICE.

WILLIAM A. EDWARDS, OF CHICAGO, ILLINOIS, ASSIGNOR TO STEWART-WARNER SPEEDOMETER CORPORATION, OF CHICAGO, ILLINOIS, A CORPORATION OF VIRGINIA.

VACUUM FUEL-FEED DEVICE.

1,321,296.

Specification of Letters Patent. Patented Nov. 11, 1919.

Application filed March 28, 1919. Serial No. 285,787.

To all whom it may concern:

Be it known that I, WILLIAM A. EDWARDS, a subject of the King of Great Britain, residing at Chicago, in the county of Cook 5 and State of Illinois, United States of America, have invented certain new and useful Improvements in Vacuum Fuel-Feed Devices, of which the following is a specification, reference being had to the accompanying drawings, forming a part thereof.

The purpose of this invention is to provide an improved construction in a vacuum fuel feed device for supplying liquid fuel to the carburetor of an internal combustion 15 engine, which shall be simpler in construction than those heretofore employed. It consists in the elements and features of construction shown and described as set out in the claims.

20 In the drawing:

The figure is a vertical axial section of a vacuum fuel feed tank embodying this invention.

The device shown in the drawing comprises the customary vacuum chamber, 1, preferably suspended within the reserve chamber or reservoir, 2, of the device, said reservoir being connected by a pipe, 3, for delivering the liquid fuel to the carburetor, 25 and having an atmosphere vent pipe, 4, leading from the upper part of the annular space between the reservoir wall and the interiorly suspended vacuum chamber. 6 is the liquid fuel supply pipe leading from a 30 low level main tank, not shown, into the vacuum chamber. 7 is the atmosphere inlet to the vacuum chamber formed in an upwardly extending fitting, 8, into which there is also connected the pipe, 9, which constitutes the suction connection to the device 35 from any suitable source of suction, as the intake manifold of the engine, not shown. In the vacuum chamber there is situated a float device for operating the atmosphere 40 valve, 10, which is carried on the stem, 11, of the float device seating downwardly in the tapered mouth, 12, which is venturi-shaped and thereby restricted at a point between the suction opening and the vacuum 45 chamber of the atmosphere inlet passage, 7. 13 is a screen for the atmosphere inlet to protect it from the entrance of dust and dirt. The vacuum chamber discharges into the reserve chamber, 2, through the discharge fitting, 14, having the flap valve, 15,

opening with the flow from the vacuum chamber into the reserve chamber as usual.

A distinguishing feature of the device consists in the construction of the float which comprises two portions, 20 and 21, positioned at a distance apart from each other on the float stem, both within the vacuum chamber, one near the bottom and the other near the top of that chamber. The dimensions of the lower portion, 20, of the float 60 device are calculated to make its buoyancy sufficient to counterpoise the weight of the parts which are carried by the float, comprising the float stem, the atmosphere valve, the upper float member, and, when they 65 are present, the liquid fuel supply controlling valve and its operating connections, and the impact of the liquid thereon, so that when said lower float member is submerged, the entire float device and all the parts carried by it tend to remain in any position in which they may be situated, that is, either with the atmosphere valve open, or with that valve closed. The dimensions of the 70 upper member of the float device, 21, are 75 calculated so that its buoyancy when substantially submerged is sufficient to force the atmosphere valve off its seat against the maximum suction which will be at any time operating in the vacuum chamber, said suction 80 obviously tending to hold the atmosphere valve seated. The result of this float construction which consists of two members 85 vertically separated from each other in the vacuum chamber the lower one slightly 90 overbalancing the weight of the parts carried, is that as the vacuum chamber fills, the atmosphere valve being closed, the float 95 being in its lower position and the suction operating through the suction connection 100 to lift the liquid from the main low level supply tank, no movement of the parts from the position shown in the figure will 105 occur until the liquid rises high enough to submerge the upper float member to a depth sufficient to cause the resulting buoyancy of that upper member to be equal to the suction hold on the atmosphere valve; whereupon slight increase of the depth of submersion beyond that point causing the buoyancy 110 to exceed the suction hold on the valve, will cause the valve to be snapped immediately away from its seat, the float rising the distance to which the upper member has been submerged, carrying the atmosphere 115

valve that distance away from its seat and admitting the full atmospheric pressure to the vacuum chamber, overcoming the suction, which is admitted through a relatively 5 small port as seen in the drawing, and thereby causing the vacuum chamber to drop its liquid contents through the fitting, 14, past the flap valve, 15, into the reserve chamber.

As the vacuum chamber is thus emptied, 10 the level of the liquid falling therein will not cause any change in the position of the float device or the valves operated by it until the level has fallen to a point a little below the top of the lower float member, 20, 15 so as to unsubmerge a portion of that float member, leaving it inadequate in respect to buoyancy to sustain the parts which are carried by the float, as described. As the liquid level falls below this point the float device will descend with the fall of the level; and when the atmosphere valve is near its seat, but before it reaches it, the suction pulling in the air past that valve will suck the valve to its seat a little before 25 it would have reached it by the fall of the liquid, slightly depressing the float device; but the valve being fully seated, the full force of the suction will continue to hold it on its seat, and vacuum being produced in 30 the vacuum chamber, the liquid will be lifted from the main low level tank to refill that chamber, repeating the cycle of operations already described.

For the purpose of the described action, 25 it is not essential that there should be any valve controlling the liquid fuel supply, but such valve may be provided for certain advantages which it may afford, and may be operated by the float device. There is this 40 advantage in having a retaining valve to close the fuel supply inlet while the vacuum chamber is being emptied into the reserve chamber; viz., that whereas in the absence of such a valve the contents of the pipe 45 leading from the main low tank to the vacuum chamber tends to fall back into the main tank and then would have to be lifted again when the vacuum chamber is next to be filled, if this can be prevented there is a 50 slight gain in efficiency in that that amount of liquid does not have to be lifted over and over again at each action of the device. If, however, the check-valve which is provided 55 to retain the contents of the fuel supply conduit in the intervals of the suction action, is so positioned that it has to be lifted by the suction, it has usually been found that the loss due to the additional 60 requirement of suction necessary to lift such a valve, more than offsets the gain in retaining the liquid column. In the construction herein shown and about to be described, the advantage of retaining the liquid column is obtained without the offsetting dis- 65 advantage of having to lift the retaining

valve at each action. As seen in the drawings, the liquid fuel supply pipe is connected for discharge upwardly through the bottom of the vacuum chamber, the inlet port, 22, being controlled by a valve, 23, carried on the stem of the float which is the stem of the atmosphere inlet valve, 10, so that the same upward movement which opens the atmosphere valve lifts the liquid fuel controlling valve, 23, to its seat, closing the port, 22. The dimension and weight of the lower float member, 20, are calculated so that the buoyancy of that member is adequate to hold the valve, 23, seated until the liquid level in the vacuum chamber falls to a point at which said lower float member is partially unsubmerged, and then the float falling, seats the atmosphere valve and opens the valve, 23, in the same falling movement, and at the instant at which the suction becomes dominant for lifting the liquid fuel from the low main tank. It will be evident that the liquid will not fall out of the pipe, 6, until it has completely evacuated the vacuum chamber; and this will never happen in the proper operation of the device when the engine is running, because the dominance of the suction which occurs as soon as the atmosphere valve closes and the valve, 23, is opened to cause the upward flow of the liquid into the vacuum chamber to recur at the instant at which the outflow from the vacuum chamber to the reserve chamber ceases, that is, when the liquid level in the vacuum chamber has fallen so as to only partly unsubmerge the lower float member.

The connection of the valve, 23, with the float so as to be oscillated for seating by the rising of the float, has the further advantage that in case of the vehicle whose engine is supplied by the device descending a grade so steep that the main supply tank at the rear of the vehicle is higher than the vacuum chamber, so that the latter might be 105 filled and even flooded and caused to overflow by gravity flow from the main tank. The rise of the float in the vacuum chamber consequent upon said chamber being filled to the proper high level, seats the valve, 23, 110 and prevents further inflow from the main tank.

It is preferred to make the entrance passage from the pipe, 6, into the vacuum chamber of venturi form, as shown, with 115 the more abruptly tapered mouth toward the valve, because it has been found that this form of passage offers a minimum resistance to the inflow of the liquid, which when the dimensions are properly proportioned will 120 be discharged through the constricted throat of the venturi passage, substantially as rapidly as it would be discharged through a passage of the full width of the widened mouth of said venturi passage. 125 130

I claim:—

1. A vacuum fuel feed device comprising a chamber having a suction connection, an atmosphere inlet and a liquid fuel supply connection; a valve to control the atmosphere inlet; a float device in the chamber actuated by change of liquid level in the chamber, and connections by which the float operates the atmosphere valve; said float device comprising two buoyant portions at different levels a substantial distance apart in said chamber, the lower of said float portions being adapted as to buoyancy to counterbalance the weight of the valve and all parts moving with it, and the other portion of the float being adapted as to buoyancy to overcome the suction on the valve.

2. In a vacuum fuel feed device such as defined in claim 1 foregoing, the suction connection opening into the atmosphere inlet passage at a point near the port at which the valve is seated, said passage being restricted relatively to said port between said suction opening and the vacuum chamber.

3. In a device such as defined in claim 1, a valve which controls the liquid fuel inlet, and connections by which the float seats said valve by its rising movement.

4. In the construction defined by claim 1, a valve which controls the liquid fuel inlet

positioned with respect to its seat for seating upwardly and connections by which the float seats said valve by the rising movement of the float.

5. In the construction defined in claim 1, a valve which controls the liquid fuel inlet, and connections by which the float both seats and unseats said valve positively.

6. In the construction defined in claim 1, a valve which controls the liquid fuel inlet, positioned with respect to its seat for seating with the inflow, and connections by which the float operates said valve for opening by the falling of the float; whereby in the intervals between the inflow said valve is held seated by the buoyancy of the lower member thereof alone without the assistance of the upper member.

7. In the construction defined in claim 1, the liquid fuel inlet being at the lower part of the vacuum chamber and of venturi form, a valve controlling said inlet and connections by which said valve is opened by the descending movement and closed by the rising movement of the float.

In testimony whereof, I have hereunto set my hand at Chicago, Illinois, this 24th day of March, 1919.

WILLIAM A. EDWARDS.
